UNITED STATES PATENT OFFICE.

EDWARD A. TUTTLE, OF BROOKLYN, NEW YORK.

IMPROVEMENT IN NURSERY-GATES.

Specification forming part of Letters Patent No. **141,677**, dated August 12, 1873; application filed December 30, 1872.

To all whom it may concern:

Be it known that I, EDWARD A. TUTTLE, of Brooklyn, Kings county, and State of New York, have invented a new and useful Improvement in Nursery-Gates, of which the following is a specification:

The invention consists in the improvement of nursery-gates, as hereinafter fully described and pointed out in the claim.

Figure 1 is an elevation. Fig. 2 is a section of Fig. 1 taken on the line *x x*.

Similar letters of reference indicate corresponding parts.

A and B are two frames connected together by the thumb-screws C C in the part A, and made adjustable as to width by means of the slot D in the part B. E are vertical slots in each of the frames. F F are slots in the part A, and attached to B are blocks with flanges G G, which are fitted to and slide in the slots F F, and serve to guide as well as hold the parts together. The outer edges or uprights H H of the two parts A B are made slightly inclined or wedge-shaped. Fitted to the uprights H H are wedge-shaped or inclined uprights I I. These pieces have flanges J, which receive and guide the uprights F as the latter slide up and down. The pieces I I have each a dovetail slot, and the uprights E have a dovetail block each, fitted to the slot,

by means of which the slides are held to the frame. (See Fig. 2.)

When the gate is to be used it is placed in the rabbets of the door or window with the screws loosened, and is extended when raised from the sill, but with the slides I I resting on the sill. Being extended so as to fill the space the screws are tightened and the gate is forced down, and the inclined surfaces of the uprights and the slides being in contact and recessed, the result is that the gate is tightly wedged in its place and made perfectly secure.

The slides I I may be made without flanges J, as other provision may be made for guiding the gate.

Having thus described my invention, I claim as new and desire to secure by Letters Patent—

A nursery-gate, made adjustable by means of slats and screws with inclined surfaces on the uprights H H, in combination with slides I I having inclines, so that when the gate is forced down it will be tightened, substantially as and for the purpose described.

EDWARD A. TUTTLE.
